UNITED STATES PATENT OFFICE.

LAURITZ W. ANDERSEN, OF WATERBURY, CONNECTICUT.

SOCKET-SHELL.

1,159,346.

Specification of Letters Patent.

Patented Nov. 9, 1915.

Application filed March 30, 1915. Serial No. 17,984.

To all whom it may concern:

Be it known that I, LAURITZ W. ANDERSEN, a citizen of the United States, residing at Waterbury, in the county of New Haven, 5 and State of Connecticut, have invented a new and useful Socket-Shell, of which the following is a specification.

This invention relates generally to socket shells, and more particularly to the manner of connecting the cap and body portions 10 of said shells; the object of the invention being to provide a simple and efficient construction for uniting the parts of the shell and at the same time hold them against 15 rotary movement one upon the other after having been so united.

With these objects in view the invention consists in the novel features of construction hereinafter fully described and set 20 forth in the claims.

In the drawings forming a part of this specification, Figure 1 is a side view of socket shell constructed in accordance with my invention. Fig. 2 is a similar view, the 25 clamping ring being broken away and shown in section in order to clearly show the other features of construction of the united parts of the shell. Fig. 3 is an inverted plan view of the cap and clamping ring, and Fig. 4. 30 is a plan view of the body portion of shell.

In carrying out my invention I employ a cap portion A, a body portion B, and a clamping ring C, these parts being constructed similar to the corresponding parts 35 shown in my application Serial Number 10,320, that is, the cap is constructed with an annular groove for receiving a clamping ring and this clamping ring is threaded to engage the upper threaded end of the body 40 portion, said upper end of the body portion fitting between the lower end of cap and the clamping ring.

The present form of socket shell may be termed a "multi-catch" shell for the reason 45 that the cap and body portions can be caught or locked together against rotary movements at a number of different points, and in fact at any desired point, and in order to accomplish this I construct the 50 lower end or skirt of the cap with vertical crimps D and at one or more points the

threaded upper end of the body B has inwardly projecting nicks or notches E which are adapted to engage the crimps of the cap, and thereby catch and hold the cap and 55 body portions against movement, the clamping ring being free to turn so as to draw the cap and body portions together.

In the drawings I have shown the body provided with three nicks but it will of 60 course be understood that one or any desired number of nicks can be used the function and operation being exactly the same irrespective of the number. This form of shell can be used in connection with a key- 65 socket or keyless socket or socket having a pull chain and it is obvious that after the cap and body portions are once brought together it will be impossible for either one to turn upon the other. The parts however, 70 can be quickly and easily disconnected when desired after the clamping ring has been unscrewed to release them.

It will thus be seen that I provide an exceedingly cheap and simple construction of 75 socket shell which will be highly efficient for the object hereinbefore referred to.

What I claim is:—

1. A socket shell comprising a cap portion, a body portion into which the lower 80 end of said cap fits, said fitting portions being provided with engaging means to prevent rotation, and a clamping ring carried by said cap and engaging said body to bind said parts together.

2. A socket shell comprising a body portion, a cap portion having its lower end fitting into the upper end of body portion, 85 said portions having engaging corrugations to prevent rotation, and means carried by 90 said cap, engaging said body, to bind said parts together.

3. A socket shell comprising a body having a threaded upper end provided with a crimp, a cap having its lower end crimped 95 and fitting into the upper end of body portion, and a threaded clamping ring carried by said cap and engaging said body portion.

4. A socket shell comprising a cap carrying a clamping ring, and a body portion 100 adapted to receive the end of cap, and be engaged by said ring, said meeting ends of

cap and body having engaging means to prevent rotation of said parts and yet permit said parts to be drawn together.

5. A socket shell comprising a cap having its lower end crimped and carrying a clamping ring surrounding said crimped end and a body portion having its upper end nicked to engage the crimped end of cap which fits

into said body, said clamping ring engaging said end of body and binding said cap and body together.

LAURITZ W. ANDERSEN.
